Primary Examiner—Stella Reid

(57) CLAIM

The ornamental design for a bottle holder, as shown and described.

DESCRIPTION

FIG. 1 is a front elevational view of the bottle holder of the present invention, the rear view being a mirror image thereof;

FIG. 2 is a left side elevational view of the bottle holder of FIG. 1, the right view being a mirror image thereof;

FIG. 3 is a top plan view of the bottle holder of FIG. 1;

FIG. 4 is a bottom plan view of the bottle holder of FIG. 1;

FIG. 5 is a top, front, perspective view of the bottle holder of FIG. 1; and,

FIG. 6 is a cross-sectional view taken along line 6—6 of FIG. 1.
